PLASTIC-FILLED MASONRY WALL

Alan L. Robertson, New Britain, Conn.

Application November 22, 1950, Serial No. 197,078

1 Claim. (Cl. 72—30)

1

This invention relates to brick constructions and more particularly to multiple-brick building units and a method of producing the same for readily constructing strong and durable foundations and walls at a minimum of expense and labor.

It is well known that the ordinary method of building brick constructions, wherein bricks are individually cemented in place, is a laborious and expensive process.

It is, accordingly, one object of this invention to provide a prefabricated reinforced multiple-brick building unit comprising a plurality of bricks firmly held together in proper spaced relationship to facilitate the erection of brick structures.

Another object of this invention is to provide a method for joining two or more bricks together in proper spaced relationship to form a practical reinforced multiple-brick building unit.

Another object of this invention is to provide a reinforced multiple-brick building unit consisting of bricks held together in proper spaced relationship whereby a strong solid wall may be constructed by first piling said units in proper vertical alignment and thereafter pouring cement into the vertical spaces between the bricks.

A further object of this invention is to provide a reinforced multiple-brick unit of the character described having self-aligning vertical reinforcing means mounted on the connection between the bricks.

A further object of this invention is to provide a reinforced multiple-brick building unit having spacer protrusions to control the distances between adjacent bricks.

A further object is to provide a device of the above nature which will be simple in construction, inexpensive to manufacture, easy to install and manipulate, compact and very efficient and durable in use.

With these and other objects in view, there has been illustrated on the accompanying drawings two forms in which the invention may conveniently be embodied in practice.

In the drawings,

Fig. 1 represents a bottom view of one of the reinforced two-brick building units.

Fig. 2 is an end view of the same.

Fig. 3 is a perspective view of one of the tubular reinforcing spacers.

Fig. 4 is a partial construction of a double-thickness brick wall made of two-brick building units.

Fig. 5 is a partial construction of a reinforced

2

triple-thickness solid wall made of three-brick building units furnished with vertical, channel-shaped reinforcement members.

Fig. 6 is a perspective view of one of the vertical channel-shaped reinforcement members shown by itself.

Fig. 7 is a top view of a modified reinforced two-brick building unit containing side and bottom spacer protrusion pins.

Fig. 8 is an end view of the same.

Fig. 9 is a perspective view of a single brick having horizontal and vertical spacer pins.

Fig. 10 is an enlarged perspective view of one of the spacer pins shown by itself.

Fig. 11 is an end view of a partial construction of a reinforced double-thickness solid wall made of the building units shown in Fig. 7 and furnished with vertical, channel-shaped reinforcement members between the rows of bricks.

Fig. 12 is a top view of the same with portions broken away.

Referring now to the drawings in which like reference numerals denote corresponding parts throughout the several views, the numeral 10 indicates a two-brick building unit embodying the invention and comprising bricks 11 and 12 held together in spaced relationship by the tubular cylindrical spacer pins 13 pressed into openings 14 in the sides of the bricks.

In accordance with the present invention the openings in the bricks may be drilled before they are fired or formed during molding of the bricks. It has been found that unfired or "green" bricks which have been molded and then air or steam dried are sufficiently firm to withstand the drilling operation. Moreover, in some cases the brick clay used may be of such consistency as not to require drying after molding, but may be drilled immediately after the molding operation. Alternatively, the bricks may be drilled after they are fired or finished. However, this is usually difficult because of their hardness and brittleness.

Each of the reinforcing spacers 13, preferably formed of sheet metal cut to size and bent into cylindrical shape, has a longitudinal slot 15 which serves to add resiliency so that the spacer may readily be force-pressed into and will retain its frictional grip within the brick openings 14. The spacer pins 13 are preferably also slightly rounded at their ends as at 16 to facilitate their being forced into the openings 14.

Referring to Fig. 4 it will be seen how a double wall with a central cavity may be constructed by use of a plurality of the two-brick building units. Not only will such a wall be much easier to build,

but since the length A (see Fig. 2) between the outer sides of the bricks may be predetermined by the use of a stop on the press which pushes the bricks together on the spacer pins, the outer sides of the finished wall will necessarily be parallel, thereby eliminating much of the usually required labor involved in furring before constructing interior walls, and in some cases, furring may be eliminated entirely.

In Fig. 5 there is illustrated a modification of the invention whereby a solid multiple-thickness brick wall or foundation may very rapidly be constructed from a plurality of multiple-brick units without the necessity of cementing each brick in place as is ordinarily done. The brick units are merely set in place one above the other in the desired position and alignment and concrete cement, mortar, or grout is thereafter poured into the vertical openings between the bricks. In this method of construction, the bricks are formed, before burning, with side openings 15a communicating with the usual recess or "frog" 16a in the bottom of the brick so that the wet cement will flow horizontally between the bricks, thereby insuring a firm bond. (In Fig. 5 the bricks are illustrated as being placed so that the recesses 16a face upwardly, rather than downwardly as is ordinarily done, in order to more clearly show the path of flow of the cement between individual bricks, as herein below explained.)

In order to reinforce the solid brick wall, each of the spacer pins 13 has assembled thereon a loosely mounted elongated reinforcing member 17. Fig. 6 shows such a reinforcing member by itself, which preferably consists of a length of wrought iron formed in channel shape and horizontally and centrally punched or drilled to provide aligned opening 18 for the passage of pins 13 therethrough. Reinforcing member 17 is preferably a little less in length than the height of two bricks so that it will not interfere with the second brick above or below. It has been found that even if some of the reinforcing members 17 are temporarily balanced in a horizontal position on their spacer pins 13, the weight of the cement rushing into the cavity between the bricks will turn them to the proper vertical position for reinforcement. Thus, though the openings 18 in the reinforcing members 17 will ordinarily be drilled at a position slightly off the longitudinal center so that they will automatically swing to vertical alignment, no special drilling or punching precautions need be taken.

Fig. 5 further shows cement which may preferably be concrete, mortar or grout, poured into the cavities between the bricks to the height of the first course of bricks, to illustrate how the wet cement spreads horizontally through the openings 15 to fill the recesses 16 between the bricks.

Figs. 7 and 8 illustrate an important modification of the two-brick building unit shown in Figs. 1 and 2, wherein bottom and end spacer pins 19, similarly fitted in pre-formed brick openings are employed to automatically space bricks both horizontally and vertically. The spacer pins 19 are similar to spacer pins 13, but shorter, and they are preferably beveled or rounded at their outer ends as at 20 so that they may easily be pressed through wet cement and against the adjacent brick surface during the construction of a wall, without the likelihood of their being obstructed by sand particles or gravel. The side or horizontal pins 19 are set in the center of one end of

each brick, as shown, and the bottom pins 19 are staggered to provide vertical stability.

Figs. 11 and 12 show a partial solid double-wall construction employing the brick units shown in Figs. 7 and 8 and including the vertical reinforcing members 17. The spacer pins 19 provide sufficient space between the bricks, both horizontally and vertically, for the flow of wet mortar or cement between bricks to insure a firm bond without the necessity of cementing each brick unit in place individually.

Referring to Fig. 8, it will be evident how, by controlling the depth to which the vertical pins 19 are forced, the overall height B of the brick units may be uniformly predetermined, thereby enabling even an unskilled laborer to build a level wall. Likewise, the overall length C (Fig. 7) may be predetermined to insure regular horizontal spacing without the necessity of special care during construction.

Moreover, by thus controlling to within close limits the overall dimensions of brick units, the architect or contractor will be able to order with accuracy the correct quantity of bricks for a given size brick construction.

Fig. 9 shows a single brick provided with horizontal and vertical spacer pins 19 suitable for rapidly constructing regular and level brick walls of single thickness.

It is to be understood that not only do the spacer pins 19 used in the bricks as herein disclosed serve to automatically space bricks to reduce the labor required to construct a workman-like wall, but said pins also serve effectively as vertical and horizontal reinforcing between the bricks of the wall when completed.

Though the invention has been described and illustrated to show a multiple brick unit for double and triple brick wall construction, it is to be understood that the invention also contemplates bricks joined end-to-end by one or more spacers 13 to provide a construction unit adaptable for use in laying a brick wall of single brick thickness. Moreover, bricks could be joined or provided with protruding pins in the manner taught by the invention to suit a variety of purposes, one of which might be an angularly joined brick unit for use in corners.

Advantages

One advantage of the building brick units constructed in accordance with the invention resides in the speed with which a brick foundation or wall may be built by their use.

Another advantage is that they greatly reduce the labor cost of brick constructions while at the same time increasing their value.

Another advantage is that the outside surfaces of multiple thickness brick walls constructed in accordance with the invention will automatically be parallel, thereby minimizing the necessity of furring the inside surface before building an interior wall.

Another advantage resides in the provision between the bricks of vertical reinforcing members which require no attention on the part of the mason in erecting the brick wall.

While there have been disclosed in this specification two forms in which the invention may be embodied, it is to be understood that these forms are shown for the purpose of illustration only and that the invention is not to be limited to the specific disclosure but may be embodied in various other forms without departing from its spirit. In short, the invention includes all the

modifications and embodiments coming within the scope of the following claim.

Having thus fully described the invention, what is claimed as new, and for which it is desired to secure Letters Patent, is:

In a solid masonry wall, a plurality of building units, each comprising a pair of spaced-apart bricks, the adjacent flat surfaces of said bricks having a plurality of aligned open recesses, a plurality of elongated slotted tubular connecting pins having their ends frictionally fitted into the recesses of both adjacent bricks, and a layer of cement located between said spaced-apart bricks in which said slotted pins are permanently embedded, and channel shaped reinforcing members pivotally mounted on each of said pins and also embedded in said cement. 15
